UNITED STATES PATENT OFFICE.

HENRY NEUMEYER, OF MACUNGIE, PENNSYLVANIA.

PENTAGRAPH.

Specification of Letters Patent No. 16,148, dated December 2, 1856.

To all whom it may concern:

Be it known that I, HENRY NEUMEYER, of Macungie, in the county of Lehigh and State of Pennsylvania, have invented and 5 made certain new and useful Improvements in Pentographs or Copying Instruments; and I do hereby declare that the following is a full, clear, and exact description thereof, reference being had to the accompanying 10 drawings, marked with letters of reference thereon to show the several parts or elements thereof.

Figure 1 is a top view of the instrument, wherein A, A, A, A, show an upper sliding 15 framing, formed with two sides and one end piece. This sliding frame, works on slides on the upper edges of an under frame B, B, made stationary to a base plate or bottom part C, C, C, as shown in the longitudinal 20 vertical sectional Fig. 2. Upon the base plate or bottom C, C, C, is arranged a bed plate D, Figs. 1, 2, 3, 4, attached to side or lateral traversing cog racks, E, E, by standards or uprights F, Fig. 2, the racks 25 being long enough to afford a sweep or play movement toward and out through the end A of the framing. Upon the bed plate D, which has slots g, g, g, g, Figs. 1, 4, are two clasp strips or holder rails H, H, formed 30 with spurs i, i, at their centers, and these strips are confined or held in place by screws or taps j, j, j, j, so as to be adjustable to and fro in the grooves g, and small rings or lifting devices k, k, are attached to the 35 centers of the clasp strip as shown in Figs. 1 and 4. Upon the bed plate D rests the drawing board D² Figs. 1, 4. Within the area of the lower or under frame or casing B, parallel to the sides thereof and arranged 40 longitudinally, are cone pulley devices L, L, of suitable length and diameter. To the butt end of one and to the smaller end of the other are gear or cog cylinders M, M² Fig. 1. To the ends of these cone pulleys 45 and cylinders are journals or axle ends. The journals of the left-hand pulley M working in holes or journal bearings 1, 1, Fig. 1, while the journals of the pulley M² on the right side work in slots 2, Fig. 1, 50 formed in the ends of the frame of the instrument, the axles of the pulley M² being attached to a sliding rack N working in a groove N², formed on the inner surface of the front end of the lower framing B, as in 55 Fig. 3. The journal or axles of the right-hand pulley M² are about $\frac{1}{8}$ of an inch

below the axles of the left-hand pulley M, as seen in Fig. 3.

In Figs. 1, 2, are shown another set or pair of cone pulleys O, O², arranged transversely or across the interior of the sliding frame A. To the back end pulley are cog gear wheels of equal size, attached to each end of the cone pulley O², and working in the longitudinal traversing racks E, E, Fig. 60 2. The front end cone pulley has but one cog or gear on its butt or larger end as at O, Fig. 2. The axle or journals of the cone pulley O² work in standard bearings O³, formed with slots O⁴, and a rack formation 70 O⁵, working on a cog pinion O⁶ Fig. 2. The cone pulley O has to its butt end a cog gear, O⁷ Figs. 1, 2, which works in a frame rack P moving in vertical uprights or ways P² formed with slots and grooves, and attached 75 permanently to the sliding frame on the inner surface of the right-hand side thereof. The journal ends of the front cone pulley also work in standard bearings attached permanently to the sides of the lower 80 framing, as at P², Fig. 2, and it will be seen that the axles or journals of the cone pulley O are elevated, above the plane of the pulley O². This frame rack P, P, is adjustable up and down, as indicated by 85 the elevation red lines P⁴, P⁴, Fig. 2, and operated by the lifting yoke piece, or adjusting strip Q, Q, Figs. 1, 3. Through the sides of the sliding frame A, A, near the front ends are square mortises or openings 90 R, Fig. 2, in which is fitted a sliding bar R², Fig. 3, grooved throughout its length as indicated by the dotted lines, and having formed to one half of its length teeth or cogs. Within the groove of this sliding 95 bar, fitted smoothly is arranged a traversing rack S, S, having formed on its left-hand end, vertical piece of tubing, or a piston socket S², in which works a pencil, or marker S³, made to elevate and depress 100 through the intervention of a spiral spring and screw thread inserted within the socket or tube S². Over the circumference of the sliding bar R², R², is a clasp device T, kept stationary by fitting into grooves formed 105 in the sides of the bar. Vertically through this clasp device is a small hole in which works vertically a pointer or follower, formed with a head, and beneath which head and around the follower is employed 110 a spiral spring, the whole as shown in Fig. 3 at T² and at T², Fig. 1.

To the end of the lower framing is attached an indicator, or graduated scale strip or bar U, U, U, Fig. 1, which scale strip has slipped over it an adjustable graduated slide block U², formed with a groove in which rests a tightening belt or pulley band U³, U³, passing over the transversely arranged cone pulleys L, L, Fig. 1, and as shown at end elevation Fig. 3. To the left-
10 hand side of the lower framing B, B, is attached another graduated scale strip V, extending almost entirely across the upper part of the instrument, and over this scale strip works a shifting fork device V², within
15 which rests a band or belt V³, passing over and around the cone pulleys, as shown in Fig. 1.

On the side of the instrument is arranged longitudinally a rod or bar W, W, having
20 on each end spur pinions W² and also a spur pinion in its center within a box bearing X, X, Figs. 1 and 5, and on the back end of the instrument is another similar rod X², X², Fig. 1.

25 The operation of the instrument is as follows: When a facsimile in size of any figure, letter, or sketch is to be made the original is placed on the drawing board D², Fig. 1, and the pointer or follower device T² is
30 set at any point or part of the thing to be copied, but the belt or band V³ V³ must be slackened or made loose by turning the winch U⁴, Fig. 1, and also observe that the traversing racks E, E, must be confined in
35 their position by the tightening screw 8, on the left hand side of the lower frame near the end thereof. Then after this adjustment of the several parts, the operator presses down the pointer or follower, and
40 while being pressed the sliding bar R², R², is moved forward if a forward line is wanted, and to the right or left also, according to requirement. It must, however, also be observed that the traversing rack S, S, must
45 necessarily be kept confined by the tightening screw R³, Figs. 1, 3, which effectually prevents the rack from working in and out, which would enlarge the figure in one direction from right to left. The copy is then
50 made by the marker or pencil, or equivalent S², under whose point is arranged a suitable board upon which the material for the copy is placed, and thus a facsimile transfer of form or configuration may be
55 readily produced. To make a diminished or reduced proportional copy of an original drawing, or configuration, the original is arranged on the board or tablet D², so that the lower part of the original is immediately
60 under the pointer or follower T² and band U³ must be shifted toward the front of the instrument near to or under the cone pulley O, while the band or belt V³, V³, must be shifted to the left side of the framing near
65 to or over the cone pulley, L, M, Fig. 1;

then, again, the traversing rack S, S, must be permitted to slide freely in the groove of the sliding bar R², R², which if moved forward causes the bed plate D, with the board or tablet D², to move in a direction opposite, 70 or from the back part to the front end of the instrument, observing however that the cog wheel O⁷, of the cone pulley O, Figs. 1, 2, be geared into the lower rack at Y, and indicated by the red lines in Fig. 2. To gear 75 the cog wheel O⁷, the rack device is raised upwardly or depressed as occasion requires. And in order to get graduated, intermediate reduced sizes, or proportions between a facsimile and the least size, the belts or 80 bands U³, V³, are shifted back or forth so as to afford the required proportion and which is indicated by the scale or sizes marked on the strip U, V, Fig. 1, to suit the purposes designed. Again, when an increased proportional size, or an enlarged 85 copy is desired, the cog wheel O⁷ must gear into the upper or top rack as shown in black ink, in Fig. 2, the rack being pushed down instead of being raised up. The 90 traversing rack S, S, must be permitted to move freely by loosening or unscrewing the screw R³, while the belts V³, must be arranged nearer the left hand side of the instrument at about one third the length of 95 the cone pulleys, from the left hand side. While the band or belt U³, V³, may be nearly in the middle of the length of the cone pulleys L M—L M². Thus the motion of the bed plate and tablet D, D², has 100 imparted to them an advance and retrograde movement, which is equal to or the same as the right and left motion or sweep of the sliding bar, while the traversing rack moves a distance equal to the advance motions of 105 the bed plate and tablet, and sliding frame A A and pointer or follower T², Figs. 1, 3. As the traversing rack moves a greater distance in proportion to the pointer, consequently the bed plate and tablet must advance or move to and fro simultaneously with the pointer, so as to make up the proportion or ratio, required longitudinally, as well as transversely, in the several movements of the instrument. Again the instrument is susceptible of being so adjusted 110 after a little experience of the operator as to admit of preserving a true proportion one way while another way the proportions may be enlarged or diminished, and by such 115 arrangement in forming or copying letters or separate characters they may be formed elongated one way and expanded another way. The instrument is also capable of delineating shorter, or longer parallel 120 lines, and perfect circles, irregular curves, ovals, etc., as well as being susceptible of being converted into an engraving instrument by substituting a graver pointed tool in place of a marker, pencil, or 125 130

tracer. In the tightening up of the belts and bands U^3 , V^3 , through the intervention of racks N , and pistons W^2 , Fig. 3, and O^5 , O^6 , Fig. 2, care must be observed not to turn 5 the winches U^4 , U^5 , Fig. 1, too often so as to tighten too much in which event the cone pulleys will not revolve smoothly or at all. In shifting the belts or bands, the winches are to be reversed, when the worm thread or 10 screw revolves the pinion cogs, and admits the shifting of the belts by aid of manipular agency. Fig. 5 is a sectional portion showing the worm or screw, working into the pinions.

15 Fig. 6 shows the tablet or drawing board detached from the bed plate D , D .

Deeming it unnecessary to enter more into further detail description of the application, and various operations of my 20 proved pentagraph instrument, and having fully described the form and construction thereof and delineated the same by suitable diagrams in detail, and believing there is no instrument similar in construction,

What I claim as new and desire to secure 25 by Letters Patent of the United States is—

1. The upper sliding frame A A A A , in combination with the under stationary frame and casing B , B , B , C , C , and the traversing cog racks E , E and uprights F , 30 Figs. 1, 2, the slotted traversing bed plate D , D , g , g , H , H with the traversing drawing board or tablet D^2 , Figs. 1, 4, the compound cog and geared cone pulleys L , L , M , M^2 , O , O^2 , O^7 , Fig. 1, the compound or 35 double and adjustable rack devices P , P , P^2 , P^3 , P^4 , Q , Q , Q , Figs. 1, 2, 3, as described.

2. I also claim the grooved sliding rack bar R^2 , R^2 , and the traversing rack S , S , 40 with its devices S^2 , T^2 , Figs. 1, 3, when combined with their pinions and cone pulleys, and the traveling carriage A , A , Figs. 1, 2, as described.

HENRY NEUMEYER. [L.S.]
